Primary Examiner — Martie K Holtje(74) *Attorney, Agent, or Firm* — Marshall, Gerstein & Borun LLP(57) **CLAIM**

The ornamental design for a watch, as shown and described.

DESCRIPTION

FIG. 1 is a top, right front perspective view of a watch showing the new design.

FIG. 2 is a right front perspective view of the watch.

FIG. 3 is a left front perspective view of the watch.

FIG. 4 is a right rear perspective view of the watch.

FIG. 5 is an enlarged front elevational detail view of the dial and hands of the watch.

FIG. 6 is a top plan view of the watch drawn to a reduced scale with respect to FIG. 1.

FIG. 7 is left side elevational view of FIG. 6.

FIG. 8 is a front elevational view of FIG. 6.

FIG. 9 is a right side elevational view of FIG. 6.

FIG. 10 is a bottom plan view of FIG. 6; and,

FIG. 11 is a rear elevational view of FIG. 6.

The broken lines depict elements of the watch that form no part of the claimed design.
